UNITED STATES PATENT OFFICE.

CHARLES W. KERSTETER, OF AKRON, OHIO.

INDUCTION-VALVE.

SPECIFICATION forming part of Letters Patent No. 681,883, dated September 3, 1901.

Application filed January 28, 1901. Serial No. 45,075. (No model.)

To all whom it may concern:

Be it known that I, CHARLES W. KERSTETER, a citizen of the United States, residing at Akron, in the county of Summit and State of Ohio, have invented a certain new and useful Improvement in Induction-Valves, of which the following is a specification.

My invention has a general relation to improvements in valves adapted to be used in automatic sprinkling systems for the protection of the interiors of buildings and their contents from fire, and has special relation to that class in which the system of pipes that extends through the building and is provided at intervals with sprinkling-jets closed by fastenings that are fusible at a determined degree of heat above that ordinarily prevailing is normally filled with atmospheric air under pressure and is connected with a pipe containing water under pressure held from entering the pipe system by valves arranged to be held closed by the air-pressure and to automatically open upon a decrease of the air-pressure due to the opening of one or more of the sprinkling-jets.

The objects of my invention are to provide a valve less liable to interruption from extraneous causes than those heretofore and now used for the purposes stated, and one which will be actuated by both fluid and spring pressure combined, or by either singly, so that a lack of pressure in the water-main will not prevent the complete and effective operation of the valve.

A further object is to obtain greater security in the valve by means of a peculiar valve-seat, and a final object is to so construct and arrange the parts that each opening of the valve, whether by reason of a fire or accident, will cause an alarm to be sounded at any determined place.

To the aforesaid objects my invention consists in the peculiar and novel construction, arrangement, and combination of parts hereinafter described and then specifically pointed out in the claims, reference being had to the accompanying drawings, forming a part of this specification.

In the accompanying drawings, in which similar reference-numerals indicate like parts in the different views, Figure 1 is a central section of my improved valve and its accom-

panying and connected parts in position to prevent the entrance of water and with the valve closed by air-pressure within the 55 sprinkling-pipe system; Fig. 2, a similar view showing the valve open and the respective position of the parts due thereto; Fig. 3, an enlarged view of a portion of the machine, illustrating the construction and arrangement of the device for sounding an alarm as soon as the valve is opened, and Fig. 4 a section at the line X X of Fig. 1.

Referring to these figures, 1 is a hollow metallic case having a front opening to reach 65 the interior closed by a cover 2, secured by bolts or other approved mechanical means, an upper branch 3, having a flange for connecting the pipe 55, leading to the system of pipes bearing the sprinklers, an oppositely-disposed branch 4, also flanged to connect it with the water-supply pipe, and a back branch 5, perpendicular to the axis of the branches 3 and 4, terminating in a cylindrical end 6 for a purpose to be stated. Above the central 70 part of the case 1 is located a circular valve-seat 7, arranged to be closed by a valve 8, having a guide-pin that runs in a spider 9 in the lower end of the branch 3. Extending across the valve-seat 7 and centrally thereof 75 and preferably integral therewith is a bar 12, extending downward from each end to a point slightly at the left of the center in straight lines. At the top of the branch 4 is an annular valve-seat 13, adapted to be 80 closed by a valve 14, in which is centrally screwed a bolt having ears 15, to which is rigidly secured one end of bar-link 16, having its opposite end pivotally mounted between ears on a bolt 17, secured in the case 90 1. Between the ears 15 is pivotally mounted one end of a bar or link 18, which is bent at an angle above its center and ends in a beveled face adapted to rest against the lower face of the right half of the bar 12. This 95 link 18 is hinged at its angle between ears 19 on the end of a hollow plunger 20, that slides in guide-rings 21 in the cylindrical end 6 of the branch 5. Within the plunger 20 is a shaft 22, secured by being screwed into 100 the left end thereof, and with its back end screw-threaded and running in a tubular nut 23, internally screw-threaded to receive it and externally threaded with threads of an

opposite and different pitch to fit in a screw-threaded opening in a cross-head 24 to constitute an adjusting device hereinafter described. The cross-head has at the top a 5 horizontal arm 25, arranged when the cross-head is moved to the left to run above and close to the top of the cylindrical end 6 of the branch 5, and has a roller 26 to prevent friction therewith, and also has in its upper 10 face a notch 27, straight at the right end and sloping at the left. Secured to and rising from the cylindrical end 6 of the branch 5 are like oppositely-disposed plates 28, supported on which is the lower half of a valve-chamber 29, provided with a cap 30, held by a 15 clamp 31 and its screw 32. The lower half of the valve-chamber 29 has a central opening in which is fitted an annular valve-seat 33 of peculiar construction in that it has a 20 lower annular channel 34 about it which in turn is surrounded by an annular integral ring, the object of which is to form a receptacle for any particles of dirt or dust that may enter the valve-case to fall into, and to 25 thereby prevent their lodging on the valve-seat and interfering with a tight joint between the valve and seat. A vertically-moving valve 35 is arranged to fit on this seat, having a guide-stem 36, that runs in a 30 guide 37, and an opening in bolt 38, screwed into the inner top of the cap 30. This valve-chamber 29 is internally connected by means of the pipe 39 with the pipe 55, and these two pipes are here used in these drawings to 35 represent a complete sprinkler system, as those in a building, and in Fig. 1 are supposed to be closed and under a pressure of air, and in Fig. 2 a leak, opening, or other means for the lowering of that pressure is 40 presumed to have taken place in the system as represented by the two pipes. Secured between ears 40 on the under side of the valve 35 is a vertically-moving latch 41, sliding in guides 42 on the inner faces of the 45 plates 28, the lower end of which latch is straight at the right and beveled at the left and is adapted to enter the notch 27 in the arm 25. The lower arm of the cross-head 24 has an opening to freely fit a guide-rod 43, 50 rigidly secured in a bracket 44, integral with and depending from the under face of the branch 5. Secured on this guide-rod 43 is a sliding collar 45, having a horizontal finger extending to the left and terminating in a downward hook 46 with an upwardly-beveled face. The collar 45 is constantly forced to the right by a spring 47 on the guide-rod 43, that abuts against the bracket 44. On the lower end of the bracket 44 is pivoted an upward hook 48, 55 having its end similarly beveled and arranged to engage the hook 46 and constantly pressed upward by a spring 49, interposed between its opposite end and the branch 5. Connected with the cylindrical end 6 of the branch 5 is a 60 hollow shield 50, inclosing the back end of the plunger 20 and cross-head 24 and its connected parts when moved to the right, as in Fig. 65

2. The objects of this case are to protect the parts from accidental disturbance after the apparatus shall be set and also to form a fulcrum for a lever for setting them. This lever (shown in end elevation in Fig. 4) has two parallel arms 51, located on opposite sides of the plunger 20, each mounted on pivots 52 and connected at their lower ends by a handle 53. Projecting from each side of the collar 45 are pins 54, arranged to lie in the path of and be engaged by the lever-arms 51 as they are rocked to the left, and these pins 54 are provided with friction-rollers to render 80 their operation easier.

The arrangement and operation of the apparatus are as follows:

Before water under pressure is introduced in the pipe connecting with the branch 4 or compressed air into the branch 3 and pipe system, as represented by pipes 55 and 39, the parts being in the position shown in Fig. 2, excepting that the valve 8 rests on the seat 7, the lever 51 is rocked by means of the handle 53 to the left, which by means of the pins 54 on the collar 45 carries the collar to the left until the hook on the collar 45 engages the hook on the latch 48 and is retained there until released by the operator. The cross-head then being free from the influence of the spring 47 is manipulated easily into the position shown in Fig. 1, thus closing the valve 14 and bracing it by the bent link 18, resting against the angle-bar 12, and at the same time the valve 35 falls upon its seat, permitting the latch 41 to enter the notch 27. The plunger 20 should be so adjusted as that when the valve 14 is absolutely tight the latch 41 rests in the notch 27, which adjustment is made by pushing the plunger from or drawing it toward the cross-head 24 by the tubular nut 23. The pipe system, as represented by pipes 55 and 39, is then charged with air under pressure and the pipe connected with the branch 4 filled with water under pressure. The hooks 46 and 48 are then disengaged by pressing up the left end of the latter, and as there will be a little play between the collar 45 and the cross-head the spring 47 will move the collar a slight distance to the right and prevent the reengagement of the two hooks.

In operation the parts remain as indicated in Fig. 1, so long as the air-pressure in the pipe system remains practically the same. If, however, a fire occurs in any room where there is a jet or sprinkling-head, so that sufficient heat is developed to fuse the binder on the sprinkler, the air will escape therefrom, thereby reducing the pressure in the pipe system. This, by reducing the pressure on the valve 35, will permit the latter to rise and draw the latch 41 from the notch 27 in the arm 25 of the cross-head 24, which will be at once forced to the right by the combined force of the spring 47 and the pressure on the under face of the valve 14, and the pressure thus obtained raising that valve and allowing the water to pass from the branch 4 into the

chamber and out through the branch 3 to the pipe system.

It will be evident from the foregoing that it would not be absolutely essential that the water-pressure should exist in order to operate the valve, as in case of its failure the spring alone would raise it and give an alarm, as in the following manner.

In giving an alarm the device shown in Fig. 10 3 is employed, which consists of an opening 56, made in the side of the cylindrical end 6 of the branch 5, and an insulated contact-finger 57, extended through it to normally press on the plunger 20 and make electrical 15 connection therewith. A notch 58 is cut in the periphery of the plunger so adjusted that when there is no decrease in air-pressure the contact-finger will rest in that notch without contact with the metal surrounding it. The 20 finger 57 is connected with one pole of an electric bell by a wire 59, and the cylindrical end 6 is connected by a wire 60 with the other post and including in connection therewith a suitable battery. Hence whenever the plunger 25 moves to the right beyond a determined limited space the circuit will be closed and the bell will ring.

I claim as my invention—

1. In a valve of the class designated, the 30 combination with an inclosing case having a branch to receive water under pressure and a branch to connect with a sprinkler-pipe system containing air under pressure of an outward-opening valve to close said second 35 branch having a bar across its seat, and an inward-opening valve to close said first branch connected with and arranged to be opened by the water-pressure, a rocking bar to hold said valve and rest against the cross-bar of 40 the opposite seat, a plunger to hold said bar, a valve connected with the sprinkler-pipe system and arranged to be held against its seat by the air-pressure in said pipe system, and to be released by a decrease of said pressure and a latch arranged to be held by said 45 last-mentioned valve to lock said plunger against movement and to release it by the rising of the valve, substantially as shown and described.
2. In a valve of the class designated, the 50 combination with an inclosing case having a branch to receive water under pressure, and a branch to connect with a sprinkler-pipe system having a valve-seat and valve with a bar across said seat, of a valve to close said first branch adapted to be rocked inward and connected with a rocking bar to press against

said cross-bar and arranged to be opened by a spring-pressed plunger, a spring-pressed plunger to hold said cross-bar and first valve, 60 a latch to hold said plunger against movement to release said valve, a valve connected with said latch and the pipe containing air under pressure arranged to be operated by the air-pressure to hold said latch in engagement with said plunger, and to release it by a decrease of said pressure, substantially as shown and described.

3. In a valve of the class designated having an inclosing case with a branch to receive 70 water under pressure, and a branch to connect with a sprinkler-pipe system containing air under pressure, and an outward-opening valve to close said second branch and an inward-opening valve to close said first 75 branch connected with and arranged to be operated by a sliding plunger, and a latch to hold said plunger against movement, and a valve operated by the air-pressure to hold said latch and to release it by a decrease of said pressure, of a spring to move said plunger to open 80 said inward-opening valve a lever to compress said spring to permit said valve to be closed and a detachable catch to hold said spring and release it when desired. 85

4. In a valve of the class designated having an inclosing case with a branch to receive water under pressure and a branch to connect with a pipe-sprinkling system containing air under pressure and an outward-opening valve to close said second branch, and an inward-opening valve to close said first branch connected with and arranged to be operated by a sliding plunger and a latch to hold said plunger against movement and a valve operated by the air-pressure to hold said latch and to release it by a decrease of said pressure and a cross-head attached to said plunger of adjusting devices consisting of a tubular nut meshing in said cross-head and surrounding a shaft mounted in said plunger and meshing thereon with threads of an opposite inclination from those on the outside of said nut to regulate the movement between the inward-opening valve and a latch-operating valve with reference to each other, 95 substantially as described. 100 105

In testimony that I claim the above I hereunto set my hand in the presence of two subscribing witnesses.

CHARLES W. KERSTETER.

In presence of—

C. E. HUMPHREY,
C. P. HUMPHREY.
